UNITED STATES PATENT OFFICE.

EUGENE R. CARICHOFF, OF SCHENECTADY, NEW YORK, ASSIGNOR TO GENERAL ELECTRIC COMPANY, A CORPORATION OF NEW YORK.

ELECTROMAGNETIC SWITCH.

1,275,844.

Specification of Letters Patent. Patented Aug. 13, 1918.

Application filed September 25, 1916. Serial No. 121,967.

To all whom it may concern:

Be it known that I, EUGENE R. CARICHOFF, a citizen of the United States, residing at Schenectady, county of Schenectady, State 5 of New York, have invented certain new and useful Improvements in Electromagnetic Switches, of which the following is a specification.

My invention relates to electromagnetic 10 switches for controlling electric circuits and more particularly to switches of this character which hold open when the current in a circuit is relatively high and close when the current drops to a predetermined value.

15 In the starting of electric motors, it has been the practice to employ a plurality of electromagnetic switches which close successively to cut out sections of resistance from the motor circuit and bring the motor up to speed. Various means have been devised 20 for controlling the operation of the switches so that they will only close when the current is at a proper value, that is, after a switch has operated to cut out a section 25 of resistance the next switch will not operate until the current has dropped to a safe value due to the speeding up of the motor.

A form of switch which has frequently 30 been proposed for this purpose is one in which a shunt coil closes the switch and a series coil, instead of controlling the circuit of the shunt coil, positively prevents the switch from closing by actually holding it open, that is, the shunt coil pulls against 35 the series or "holding out" coil. A switch of this general character is disclosed in patent to Fraser #655,335. The difficulty with the device shown in this patent is that the value of current in the holding out winding 40 at which the switch will close depends upon the pull of the shunt coil, which of course will vary with the voltage and also with the temperature of the coil. In other words, the "setting" of the switch, i. e., the motor current value at which it closes, changes 45 with change of voltage. It also closes at one value of current in the series coil when the shunt coil is cold and another when it is at its operating temperature which is ordinarily about 60 degrees C.

50 Attempts have been made to overcome this difficulty by having an auxiliary member, which is operated by the shunt coil, place a spring under tension which tends to move the switch member to closed position. This

tendency is opposed by the series coil when the current is high and when the current drops to a predetermined value, the spring overcomes the pull of the series coil and closes the switch. Such an arrangement is 60 unsatisfactory for the reason that the switch is closed by a spring instead of by electromagnetic pull, and it is impossible to obtain the required pressure between the contacts. The spring weakens as the switch member 65 moves toward closed position, and the pressing together of the contacts is accomplished when the spring is weakest. As the parts wear, the pressure between the contacts decreases.

70 One of the objects of my invention is to improve the electromagnetic switch of the type above described by providing means whereby the switch member will be operated so as to be positively closed and wiped 75 home by the magnetic pull of the shunt coil when the current in the series coil drops to a predetermined value, this being accomplished by the provision of means whereby the switch member is held open by the shunt 80 coil but will be released therefrom when the current reaches a proper value. In one form of my invention I employ a hammer-blow device which is moved to operative position by the shunt coil but is held in operative position by the series coil. When the current in the series coil drops to a predetermined value the hammer-blow device operates and releases the switch arm from the open position in which it is held by the pull of the 85 shunt coil thereby permitting it to be closed by the shunt coil. The result of this arrangement is that the value of current in the series coil at which the switch closes will be independent of the variations in pull of the 90 shunt coil due to variations of voltage and other causes and the switch will be closed magnetically.

95 In the accompanying drawing illustrating one form of my invention Figure 1 is a 100 side elevation of a complete electromagnetic switch embodying my improvements; Fig. 2 is a front elevation of the same, and Figs. 3, 4 and 5 show in outline the various positions which the switch assumes in practice.

105 Referring to Figs. 1 and 2, 10 represents an energizing winding which is shown as a fine wire winding suitable for use as a shunt winding on an electromagnetic switch for 110

controlling motor circuits. This winding is arranged to energize the magnetic structure composed of core 11 mounted in and projecting through block 12 of brass or other non magnetic material, and a pole piece 13 connected with the core at its lower end. This pole piece has a projecting portion 14 bent upward at right angles, this projection being surrounded by a copper band 15 for the purposes hereinafter set forth. A switch member 16 is pivoted at 17 to ears on the block 12 and is provided with a contact 18 which co-operates with a stationary contact 19 mounted upon the insulating base 20. The contact 18 is pivoted at 21 to the main portion of the switch arm and is pressed in the direction of the fixed contact 19 by a spring 22 so as to provide a yielding engagement between the two contacts which wipe or roll upon each other in a well understood manner. The main portion of the switch arm consists of the armature portion 23 which co-operates with the core 11 and a tail portion 24 at an angle thereto. This switch member is so pivoted and weighted that it normally assumes the position shown in the drawing, so that the tail piece 24 rests against the adjusting screw 25 of non-magnetic material. This screw adjusts the gap between the tail piece 24 and the bent portion 14 of the pole piece 13 and is moved in and out by turning the knurled head 25'. This gap 26 determines the holding out pull exerted upon the switch arm. Pivoted on the pivot 17 is a frame of non-magnetic material composed of side pieces 27 and a cross connecting bar 28 which is off-set out of the plane of the members 27. The off-set is sufficient to bring the cross bar 28 into close proximity to the tail piece 24 but not touching it, when the latter is in its normal position shown in the drawing. One of the members 27 has a projection 29 extending downward and terminating in an armature 30 of magnetic material co-operating with the core 31 of a magnet having a winding 32. This winding it will be observed is a heavy or coarse winding of a type suitable for carrying the armature current where the switch is used for controlling an electric motor. Pivoted on the pivot 17, between the side pieces 27, is an armature 33 the free end of which co-operates with the projecting portion 14 of the pole piece 13 so as to be attracted thereby. Between this armature 33 and the off-set cross piece 28 is a spring 34 which is compressed when the armature 33 is attracted by the projecting pole piece 14, thereby exerting a pressure upon the frame 27 which is resisted by the core 31. When, however, the pull of the core 31 decreases sufficiently due to the drop of current in the winding 32, the spring will preponderate, whereupon the frame will respond to the

spring pressure and deliver a slight hammer blow to the tail piece 24, thereby releasing the latter from the projection 14 of the pole piece 13.

As thus constructed and arranged the operation of my device will be as follows: Assuming that the winding 10 is energized by being connected across a circuit which is of substantially constant potential and the winding 32 connected to a circuit in which the current is variable, as for instance in the armature circuit of an electric motor. If the current in the circuit to which this winding 32 is connected is of such a value that the switch should not close, the switch member will be held open and the parts will assume the position shown in Fig. 4. It will be noted by reference to Figs. 3 and 4 that the only part that has moved is the armature 33, which is moved into engagement with the projecting pole piece 14. The copper band 15 retards the rise of flux in the projection 14 and softens the blow of the armature 33 against the projection. The frame composed of the side bars 27 is held in place by the pole piece 31 and the spring 34 is therefore compressed but the switch arm is held in its normal position by the pull across the gap 26. When the current in the winding 32 drops to the proper value, the armature 33 will be released, whereupon cross member 28 will strike the tail piece 24 a slight blow which will release it from the influence of the pole piece 14, whereupon the pole piece 11 will attract the switch arm and move it to closed position as shown in Fig. 5.

What I claim as new and desire to secure by Letters Patent of the United States, is:

1. An electromagnetic switch comprising an energizing winding and a magnetic structure therefor, a switch arm normally in open position and held in said position by magnetism set up by said winding, a member moved upon the energization of said winding to set up a force tending to release the switch arm and move it in a closing direction, a holding out winding and means for restraining the said releasing force until the current in the holding out winding drops to a predetermined value. 105

2. An electromagnetic switch comprising a switch arm, an energizing winding and a magnetic structure therefor which holds it in open position and moves it to closed position, a member moved by the magnetic force set up by the said winding to set up a force tending to release the switch arm from the open position in which it is held so that it will be closed by said winding, a holding out winding and means for restraining the releasing force until the current in the holding out winding drops to a predetermined value. 110

3. An electromagnetic switch comprising a switch arm, an energizing winding and a

magnetic structure therefor which holds it in open position and moves it to closed position, a member moved by the magnetic force set up by said winding to store energy for 5 releasing the switch arm from the open position in which it is held by the winding, a holding out winding and means whereby the stored energy causes a hammer blow to be delivered to the switch arm to permit the 10 latter to be closed by the operating winding when the current in the holding out winding drops to a predetermined value.

4. An electromagnetic switch comprising an energizing winding and a magnetic structure therefor, a switch arm normally in 15 open position and held in said position by the magnetic force set up by said winding, a hammer blow device moved to operative position by said winding and arranged to release the 20 switch arm from the open position in which it is held by the said winding so that it will be closed by the winding, a holding out winding and means controlled thereby for restraining the hammer blow device until the 25 current in the holding out winding drops to a predetermined value.

5. An electromagnetic switch comprising an energizing winding and a magnetic structure therefor, a switch arm normally in

open position and held in said position as 30 well as in the closed position by the magnetism set up by said winding, a hammer-blow device moved to operative position by said winding and arranged to release the switch arm from the open position in which 35 it is held by the said winding so that it is closed by the winding, a holding out winding and means controlled thereby for restraining the hammer blow device until the current in the holding out winding drops 40 to a predetermined value.

6. An electromagnetic switch comprising an energizing winding and a magnetic structure therefor, a switch arm normally in 45 open position and held in such position as well as in closed position by the magnetism set up by said winding, a member moved by the said winding to set up a force tending to release the arm from the winding and move it in the closing direction, a holding 50 out winding and means for restraining the said releasing force until the current in the holding out winding drops to a predetermined value.

In witness whereof, I have hereunto set 55 my hand this 23rd day of September, 1916.

EUGENE R. CARICHOFF.
